AIRPLANE

Ivan H. Driggs, Montgomery County, Md., Abraham
Hyatt, Washington, D. C., and Frampton E. Ellis, Jr.,
Montgomery County, Md.

Application July 10, 1952, Serial No. 20,558

Term of patent 14 years

(Cl. D71—1)

(Granted under Title 35, U. S. Code (1952), sec. 266)

The invention described herein may be manufactured and used by or for the Government of the United States of America for governmental purposes without the payment of any royalties thereon or therefor.

Fig. 1 is a perspective view of the airplane, it being shown in a vertical climbing position.

Fig. 2 is an elevational view of the airplane.

Fig. 3 is a front view of the airplane.

We claim:

The ornamental design for an airplane, as shown.
